UNITED STATES PATENT OFFICE

158,580

VENDING MACHINE

George Bruce Kamp, Lansdowne, Pa., assignor to American National Dispensing Co., Lansdale, Pa., a corporation of Pennsylvania

Application May 28, 1949, Serial No. 2,956

Term of patent 14 years

(Cl. D52—3)

To all whom it may concern:

Be it known that I, George Bruce Kamp, a citizen of the United States, residing in Lansdowne, county of Delaware, Commonwealth of Pennsylvania, have invented a new, original, and ornamental Design for a Vending Machine, of which the following is a specification, reference being had to the accompanying drawings, which form a part thereof.

I claim:

The ornamental design for a vending machine, as shown.

GEORGE BRUCE KAMP.
